[57] CLAIM

The ornamental design for a fluorescent display tube for
large screen video matrix array, as shown and de-
scribed.

DESCRIPTION

FIG. 1 is a front elevational view of a fluorescent dis-
play tube for large screen video matrix array, showing
one embodiment of our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a cross-sectional view thereof as taken along
line 7—7 of FIG. 1, all inner mechanisms being omitted;

FIG. 8 is a cross-sectional view thereof as taken along
line 8—8 of FIG. 1, all inner mechanisms being omitted;

FIG. 9 is a front elevational view of a fluorescent dis-
play tube for large screen video matrix array, showing

a second embodiment of our new design;

FIG. 10 is a rear elevational view thereof;

FIG. 11 is a right side elevational view thereof;

FIG. 12 is a left side elevational view thereof;

FIG. 13 is a top plan view thereof;

FIG. 14 is a bottom plan view thereof;

FIG. 15 is a cross-sectional view thereof as taken along
line 15—15 of FIG. 9, all inner mechanisms being omit-
ted; and

FIG. 16 is a cross-sectional view thereof as taken along
line 16—16 of FIG. 9, all inner mechanisms being omit-
ted.
